UNITED STATES PATENT OFFICE.

JOSEPH K. DAVISON, OF PHILADELPHIA, PENNSYLVANIA, ASSIGNOR TO
FRANK H. THOMAS, OF WASHINGTON, DISTRICT OF COLUMBIA.

DESIGN FOR A BADGE.

SPECIFICATION forming part of Design No. 32,648, dated May 15, 1900.

Application filed April 20, 1900. Serial No. 13,669. Term of patent 31 years.

To all whom it may concern:

Be it known that I, JOSEPH K. DAVISON, a citizen of the United States, residing at Philadelphia, in the county of Philadelphia and State of Pennsylvania, have invented and produced a new and original Design for Badges, of which the following is a full, clear, and exact description.

In the accompanying drawings, forming part of this specification, I have shown my design in Figure 1 in front elevation and in Fig. 2 in longitudinal section.

The leading or material feature of my design, as shown in the drawings, consists of the ornamental bar *a*, executed in high relief and having as the central and dominant feature the image of a man in oriental costume and bearing a scepter and mounted upon the image of a camel. In the background is a

representation of a rising sun and to the on-²⁶ looker's right palm-trees and to his left pyramids. A miniature simitar is suspended from this bar, and a crescent upon which is a medallion keystone is hung from the simitar, and beneath and from the crescent depends ²⁵ a medallion representative of Washington.

Having described my invention, what I claim as new, and desire to secure by Letters Patent, is—

The design for a badge, substantially as ³⁰ shown and described.

In testimony whereof I have hereunto set my hand this 18th day of April, A. D. 1900.

JOS. K. DAVISON.
